UNITED STATES PATENT OFFICE

2,445,495

MULTIPLE TOWEL HOLDER AND
DISPENSER

Jacques Rouss, Los Angeles, Calif.

Application May 14, 1945, Serial No. 593,578

7 Claims. (Cl. 312—37)

1

This invention relates to improvements in towel holders. More particularly, it relates to improvements in controlled multiple towel holders. It also relates to coin-controlled means for dispensing towels.

An object, among others, of the invention is a provision of efficient, simple and relatively inexpensive means controlled by a coin for releasing towels for drying hands, etc.

Another object relates to improved means for storing clean and soiled towels.

These and other objects and advantages will appear more fully hereinafter.

In the drawings:

Fig. 1 is a perspective view of the cabinet embodying my invention.

Fig. 2 is a sectional view on the line 2—2 of Fig. 1.

Fig. 3 is a detailed perspective of the soiled towel rack shown at the bottom of Fig. 1.

Fig. 4 is a top plan view of the coin slide and gripping device in position for the withdrawal of a towel.

Fig. 5 is an enlarged detailed section showing the clean towel storage means and the rack for transferring towels to the removable soiled-towel storage rack, and showing the towel ready for use before being dropped to the soiled-towel storage rack.

Fig. 6 is a fragmental sectional view of the supplemental rack.

Referring to the drawings in detail, I have shown a cabinet 10 having a front wall 11 and a back wall 12.

The back wall 12 has a section 12a, which is hinged to a top section 12b, which is in turn hinged to the front wall 11, so that walls 12a and 12b may be lifted up and swung upon each other in order to permit the insertion of clean towels into the clean-towel storage main trackway or rack 16, as will more fully hereinafter appear.

Side walls 13, together with a forward wall 11a and the intermediate wall formed by the lower portion of the front wall 11, form a well 14 for the storage of soiled towels.

The clean-towel supply is shown at 15, held in place by means of a channel-shaped clean-towel rack 16, supported in the cabinet between the side-walls 13.

The towels have grommets 17 and are attached to plates 18 by means of links 19 forming towel holders.

The plates, in turn, have apertures 20, and are

2

supported on pins 21, which also support a pair of rollers 22.

These rollers are adapted to be inserted one on top of the other in the rack 16, the plates 18 projecting from the rack 16 through a slot 23 in the rack 16.

This slot is present in all parts of the rack or trackway, as well as in the soiled towel-storage rack, as will hereinafter more fully appear.

The slot, which is vertical, is clearly illustrated in Fig. 3.

It will be readily understood that the rollers are placed one upon another in the clean-towel storage rack 16.

The front wall 11 has a window 24 for the purpose of indicating when the supply of clean towels is exhausted or nearing exhaustion.

To accomplish this purpose, there is a gravity-operated indicator 25 having a support 26 resting upon a foot piece 27, which in turn rests upon the top most of the towel rollers 22.

The indicator 25 is connected to the support 26 by side members forming a bracket 28, as shown in dotted lines in Figure 2, and the lower ends of the support 26 extend forward resting upon the rollers 22 of the towel holders so that as the towels move downward, the support 26 and the indicator 25 will also move downward until the indicator shows through the window 24. When the indicator shows through the window 24, the towel rack is empty.

When the towels are nearing exhaustion, the indicator 25 will register with the window 24 to indicate that fact by any suitable symbol or lettering.

The coin operating means may be any one of a number of suitable well-known means for actuating the release of a towel upon the insertion of a coin, such as in Patent Nos. 1,908,380, 1,908,752, 1,941,638, 1,992,642, 2,026,921, 2,049,597 and 2,058,503.

In general, the insertion of a coin in the aperture 29 will permit the plunger 30 to push the plate 31 forward, which otherwise would not be moved forward.

This coin device may be mounted in a casing 32 enclosing a coin box 33.

Pivotedly mounted on and extending in front of the plate 31 are a pair of grippers 34, which are normally resiliently held together, as shown in Fig. 4 in full lines by means of springs 35, mounted on plate 31 and extending along the outside of the grippers, as clearly shown in Fig. 4.

These gripper members 34 are provided with cam heads 36 in such a manner as to spread the

gripping members upon contact with the rollers until the heads ride outside the rollers and past the rollers when they will snap together behind the rollers.

Integrally formed with the plate 31 is a base plate 38, which is located between the grippers 34, and the shoulders 37 thereof limit the movement of the grippers toward each other.

The grippers may move in a guideway 39, adapted to guide the movement of the grippers backwardly and forwardly in a well defined pathway, and the plate 31 may be connected by means of a pair of vertical piers 40 to the coin mechanism above.

The cabinet is provided with a roller rack below the guideway 39. The rack is adjustably supported in brackets 41, the ends of which are provided with slots 42 in which a roller 43 at the upper end of the rack is mounted. Additional rollers similar to the roller 43 are suspended therefrom by links 44 at the ends thereof.

An advantage of these rollers is that they are located to have the clean towels rest upon them so as to facilitate the withdrawal of the bottom clean towels.

There may be a number of these rollers 43, and when the grippers withdraw the bottom clean towel, these towels will ride against the rollers 43 and facilitate their withdrawal thereby.

The grippers, upon the insertion of a coin, will withdraw the clean towel at the lower end of the rack 16 through the guideway 39 and through an opening in the upper part of the intermediate partition forming the lower portion of the front wall 11. The grippers 34 draw the clean towel along the guideway 39 with the towel holder passing through the slot 39a to the opening 39b in the lower surface of the casing 32.

When a roller 22 reaches the opening 39b it will drop by gravity onto the curved upper portion of the rack 45, as particularly seen in Fig. 5, and then the towel is ready for use. It should be understood that there is a slot 39a in the guideway 39 to permit the plate 18 to ride along under the rollers 22.

There also may be provided a short semi-circular supplemental rack 46 having arms 47 and 48.

This rack may have a cut-out 49 registering with a cut-out 50 in the rack 45.

The supplemental rack 46 may be welded to the rack 45 where they line up when the cut-outs are in registry.

This supplemental rack will also have a slit 51 for the chain of the towel in the same manner as the rack 45.

This supplemental rack will serve to permit towels to be used by persons standing at the sides of the cabinet by drawing the towels sidewise while at the same time a towel may be used by a person standing at the front of the cabinet.

The rack 45 will lead down into the soiled-towel well 14 to register with the removable soiled-towel rack 52.

The removable soiled-towel rack 52 is supported in a bracket 53, which may be provided with a lock 54.

The removable rack 52 may have a closed end 55 and rest on a base 56.

It is believed that the operation will be manifest without much further description.

It will be understood that the delivery man may unlock the lock 54 and remove the removable rack 52 and the soiled towels thereon and

substitute an empty removable rack for new soiled towels, and lock the same.

He also will unlock the lock for the hinged doors on top of the cabinet and lift out the indicator and insert a new supply of clean towels, and then replace the indicator on top of the top-most clean towels.

It will also be understood that a large number of towels may be stored in the clean-towel storage space, especially since the rollers may be made almost as small as desired.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variation and modifications as come within the scope of the appended claims.

Having thus described my invention, what I claim as new and desire to secure by Letters Patent is:

1. In a towel holding device of the class described, a cabinet, a plurality of towels therein, a set of rollers attached to each towel, a trackway for said rollers, and a coin-controlled, manually operated gripping device adapted to grip a single set of rollers and to pull said rollers with the attached towel from said cabinet.

2. In a towel holding device of the class described, a cabinet, a plurality of towels therein, a set of rollers attached to each towel, a trackway for said rollers, and a coin-controlled, manually operated gripping device adapted to grip a single set of rollers and to pull said rollers with the attached towel from said cabinet, said trackway continuing continuously downwardly into a lower soiled towel section of said cabinet, whereby said towels may fall by gravity after use.

3. In a towel holding device of the class described, a cabinet, a plurality of towels therein, a set of rollers attached to each towel by means of a grommet, a trackway for said rollers, and a coin-controlled, manually operated gripping device adapted to grip a single set of rollers and to pull said rollers with the attached towel from said cabinet.

4. In a towel holding device of the class described, a cabinet, a plurality of towels therein, a set of rollers attached to each towel, a main trackway for said rollers, and a coin-controlled, manually operated gripping device adapted to grip a single set of rollers and to pull said rollers with the attached towel from said cabinet, and a supplemental trackway outside said cabinet, connecting with said main trackway and extending on either side of said main trackway and at substantially right angles thereto.

5. In a towel holding device of the class described, a cabinet, a plurality of towels therein, a set of rollers attached to each towel, a trackway in the upper part of said cabinet and protruding horizontally from said cabinet for said rollers, and a coin-controlled, manually operated gripping device adapted to grip a single set of rollers and to pull said rollers with the attached towel from said cabinet, a second trackway beginning at a point below the horizontal portion of the first-mentioned trackway and adapted to receive said rollers by gravity from said first-mentioned trackway, said second trackway extending continuously into a lower soiled towel bin, whereby said rollers and said attached towel may be delivered by gravity to said bin.

75

6. In a towel holding device of the class described, a cabinet, a plurality of towels therein, a set of rollers attached to each towel, a trackway for said rollers, and a coin-controlled, manually operated gripping device adapted to grip a single set of rollers and to pull said rollers with the attached towel from said cabinet, a second set of fixed rollers in said cabinet adapted to contact said towels and reduce the friction of their removal from said cabinet.

7. In a towel holding device of the class described, a cabinet, a plurality of towels therein, a pair of rollers with towel connecting means between them and a slotted trackway adapted to contain said rollers, but not said towel holding means, and a coin-controlled, manually operated gripping device adapted to grip a single set of rollers and to pull said rollers with the attached towel from said cabinet.
